W. B. GRAY,
DEVICE FOR MARKING EARTHENWARE,
APPLICATION FILED APR. 16, 1914.

Patented Oct. 19, 1915.

1,157,380.

UNITED STATES PATENT OFFICE.

WILLIAM BEALL GRAY, OF LOUISVILLE, KENTUCKY, ASSIGNOR TO MARTIN J. BANNON,
OF LOUISVILLE, KENTUCKY.

DEVICE FOR MARKING EARTHENWARE.

1,157,380.

Specification of Letters Patent.

Patented Oct. 19, 1915.

Application filed April 16, 1914. Serial No. 832,225.

To all whom it may concern:

Be it known that I, WILLIAM BEALL GRAY, a citizen of the United States, and a resident of Louisville, in the county of Jefferson and State of Kentucky, have made certain new and useful Improvements in Devices for Marking Earthenware, of which the following is a specification.

My invention is an improvement in means for marking earthenware, especially of that character of earthenware which is formed in sections, and the sections are afterward separated from each other, for storage in different places, or for use at different times, wherein each section of each entity is provided with a series of numerals or other distinguishing marks of a consecutive character, the said distinguishing marks being impressed on the various sections while the material of the sections is capable of taking and holding an impression, and arranged below the general level of the surface of the sections, to prevent injury or breakage to the said distinguishing marks, the said distinguishing marks being adapted to be removed in such manner that the sections of each entirety will be readily identified.

In the drawings: Figure 1 is a perspective view of an article composed of separable sections, and marked in accordance with the improved method, Fig. 2 is a similar view showing a modified method of marking, Fig. 3 is a section on the line 3—3 of Fig. 4 looking in the direction of the arrows, Fig. 4 is an enlarged section on the line 4—4 of Fig. 1, looking in the direction of the arrows, Fig. 5 is a top plan view of a portion of a die for forming the marks, Fig. 6 is a transverse section of the result of impressing the same, and Fig. 7 is a front view of another series of marks.

In the preparation of earthenware articles, as for instance separable earthenware conduits of the character shown and described in my co-pending applications, Serial No. 723,206, filed September 30, 1912 (Patent No. 1,110,127), Serial No. 782,661, filed August 2, 1913, the upper of the half or portion of each section of the conduit is removed prior to the laying of the conduit, and the lower portions or halves are laid, after which the pipes to be supported are inserted or placed, and the upper halves or portions of the sections are then placed on

the lower halves or portions and sealed to the said lower halves or portions.

It will be evident that each upper half or portion of each section of the conduit must be placed on the lower half or portion from which it was originally divided, otherwise the lines of fracture will not coincide, and there will be flaws in the joint between the portions of the sections. It is also a rule that frequently not only days but weeks will elapse between the laying of the lower halves of the portions of the conduit, and the laying of the upper halves or portions, and during that time the two portions of each section are liable to injury and are subjected to usage, such that ordinary identifying marks, of chalk, paint, or the like, would be injured, defaced or entirely removed, and the result will be that an indefinite amount of experiment and fitting would be necessary before the various portions of the sections could be properly assembled.

The present invention is designed to provide a certain infallible method of identifying the several portions of any article, in order that there may be no difficulty whatever in identifying the missing portion.

In Fig. 1 is shown an article consisting of two portions or sections, the said portions or sections being designated A and B respectively. The article is provided with score lines C between the sections for permitting a chisel or the like to be inserted, to separate the sections or portions from each other.

The article shown is a section of pipe supporting conduit, forming the subject matter of my above-mentioned co-pending applications, and each section of conduit is provided with inner and outer score lines, the score lines being separated at their adjacent edges by a portion of the material of the conduit. The upper and lower portions of the sections of the conduit are separated by rapping and introducing a chisel into the cuts or scores and making pressure to fracture this above-mentioned portion of the material. It is obvious that to secure a proper fit, and a water-tight joint, each upper section must be fitted to the lower section or half from which it was originally removed, and the scores are afterward filled with cement to seal the sections or portions

together. Each section or portion A and B of the article is provided on its outer surface and preferably near one of the score lines, with a rectangular depression D, the walls d being preferably beveled or inclined, as shown. An approximately plane surface is thus provided at the bottom of the depression, the long axis of the said plane surface being preferably parallel with the long axis of the conduit. On the said plane surface a series of designating marks or characters E are provided, the said designating marks or characters being raised above the general level of the plane surface, but not to the height of the walls d of the said depression. That is the highest points of the said designating marks or characters are below the general surface of the conduit. Preferably the characters used are such as follow a regular order, and may be arranged consecutively, the reference numerals 1 to 0 being used in the present instance. Before the several sections or portions of each article, as for instance the upper and lower halves of a section of conduit, are separated, certain of the designating characters are removed, the same characters or marks being removed from the two halves or portions of the article.

The method of utilizing the distinguishing marks is as follows: For the sake of convenience sections of pipe conduit will be used for illustration. For example, it will be stated that for instance, 20 tons of a certain size of pipe are scattered along the trench in which they are to be laid. The lengths of the sections are approximately two feet, and before commencing the laying of the pipe, the top pieces or halves are separated and stored out of the way, so that they will not be broken by the heavy pipe distributed along the trench and being placed in the same. The upper halves of the pipe will probably lie for a fortnight before use, and when they are used the upper portion of each length must be placed with the lower portion with which it was originally connected.

Before separating the portions of the lengths, certain of the designating marks are removed from the portions of the said length of conduit. For instance, each half of each length is provided with a series of numerals arranged in consecutive order, and in a depression, such that the highest points of the letter are below the periphery of the pipe, or below the surface of the article, whatever it may be, and preferably, though not necessarily, the series are arranged near the point of fracture, that is near the dividing line that separates the section of the article.

Before separating any length, certain of the numerals of each section of the length are removed or noticeably marred, with a

hammer and cold chisel, or any other desired manner. As for instance, with the first length, the numeral 1 would be chipped off of the upper section, and the same numeral would be chipped off from the lower section. With the second length, the numeral 2 would be chipped off from each section, both upper and lower sections. From the third length the numerals 3 would be chipped off or otherwise removed from both sections. With the fourth length, the numerals 4 would be removed. The tenth length would be marked for identification by removing 0 from both sections, and the eleventh length by removing the numerals 1 and 0; the twelfth by removing 2 and 0, and in such manner by removing the succeeding numeral and 0 from each portion or length, removing 9 and 0 for the nineteenth length. For the twentieth length 1, 2 and 0 might be removed, 1, 3 and 0 for the 21st, and so on, 1, 9 and 0 marking the twenty seventh length or section. The twenty eighth length could be marked by removing the numerals 2 and 3 and the succeeding lengths in the same manner, by removing the numerals 2 and 4, 2 and 5 and so on. Succeeding combinations can be formed by the numerals of each series 2, 3; 3, 4; 4, 5; 5, 6; 6, 7; 7, 8; 8, 9; and in like manner. In addition, the lengths might be separated into series, a serial letter or other distinguishing mark being placed at the beginning of the numerals or at the end, as for instance one series might be designated as A, and a second as B and in like manner.

When articles of different size are in question, the same marks or numerals might be removed from two articles of different size without causing any confusion. This would apply in pipe conduits, to sections of different diameters or of different lengths. It is obvious also that the same combinations of distinguishing marks might be removed from articles of the same size, provided the several lots from which the same distinguishing mark were removed, were widely separated, or on widely separated portions of the work.

In separable pipe conduits, on account of the fact that the lower section is laid in the trench and the pipe is placed before the upper section is placed, it is preferable to place the identifying marks on the inside of the lower section, as shown in Fig. 2. In this figure the conduit A' has its upper section provided with the depressed plane surface D' on its outer face, while the plane depressed surface D² is on the inner face of the lower section. It is not essential that the lengths or the articles be laid in any specified position, but merely that the portions of each length or article have a common identifying mark different from the identifying marks of all of the other lengths or

articles near. Neither is it necessary to entirely remove the identifying marks, since the said marks may be marred in a noticeable manner.

5 It will be understood that the identifying marks may be formed on the articles in any desired manner, as for instance by a hand stamp, having a flat plate provided with sunken numerals, or by a wheel having on its periphery sunken numerals. The invention consists in the provision of the identifying marks in a depression, wherein the highest points of the identifying marks are below the general surface of the article.

10 15 While the invention is shown in connection with a length of conduit, it is obvious that it will be equally applicable to any other article made in sections, wherein the sections were intended to be divided, and to 20 be later reunited. The marks are made before the baking or hardening of the article, when the material from which the article is formed will receive an impression.

25 It will be obvious that while the method might be followed by providing raised marks, or depressions, not below the general level, the present method of forming the marks is preferable, for the reason that marks so arranged cannot easily become accidentally marred or broken.

30 In Fig. 5 a portion of a die is shown, especially adapted for forming the marks on the green conduit sections or lengths. Fig. 35 40 45 50 55 60 65 70 75 80 85 90 95 100 105 said die comprises a plate G having its central portion raised, as shown at g, above the level of the edge of the plate, and on the said raised portion depressions g' are formed, the said depressions being shaped to form the marks desired, as for instance letters in the present instance. The depression forming each letter is a single depression, all of the parts communicating as shown, and from each depression a plurality of vents g² lead to the general level of the plate. The vents are of greatest depth and width at the depression which forms the mark, and they gradually decrease in depth and width to practically merge in the general level of the plate. With this arrangement, raised marks are provided in the conduit length B, as shown in Fig. 6, the elevated characters E being above the general level of the depression D in which the letters or marks are arranged. The provision

of the vents prevents the trapping of air in the depressions g' when the die is pressed on to the conduit length, and since the air can escape there will be a cleaner clear cut mark.

In Fig. 7 another arrangement of marks is shown, wherein both the letters of the alphabet and the numerals 0 to 9 are used. With this arrangement a somewhat greater latitude or variety of arrangement is permitted. For instance, with the characters shown, the first length of conduit would be marked by breaking away or marring the numbers 1 and 1. The second length would be marked by breaking or marring the numerals 2 and 2, and in like manner until the 10th length were reached, when the numerals 0 and 0 would be used. The second ten lengths would be identified by breaking away or marring characters A1 to A0, the third ten by marring the characters B1 to B0, the fourth ten by the characters C1 to C0, and in like manner the fifth ten by using the characters D1 to D0. Thus fifty lengths would be marked, and in the arrangement shown 500 lengths might be properly identified, without the necessity of using more than two digits in any one length. With the conduit composed of two feet sections, the arrangement described would identify 1000 feet of conduit, without requiring the breaking away or marring of more than two digits on each length. The arrangement could then be repeated, since there would be but slight danger of confusion.

I claim:

1. An identifying means for earthen articles composed of separable sections, comprising a depressed ground on each section, each ground having raised characters, the highest portions of the characters being below the surface of the article, and the arrangement of the characters on the sections of the same article being the same.

2. An identifying means for earthen articles composed of separable sections, comprising a depressed ground on each section, each ground having raised characters, and the arrangement of the characters on the sections of the same article being the same.

WILLIAM BEALL GRAY.
